UNITED STATES PATENT OFFICE.

HENRY D. MILLS, OF FISHS EDDY, NEW YORK, ASSIGNOR OF ONE-HALF TO
PATRICK H. LAWLESS, OF EASTBRANCH, NEW YORK.

WINDOW-SCREEN.

SPECIFICATION forming part of Letters Patent No. 709,346, dated September 16, 1902.

Application filed July 3, 1901. Serial No. 67,050. (No model.)

To all whom it may concern:

Be it known that I, HENRY D. MILLS, a citizen of the United States, residing at Fishs Eddy, in the county of Delaware and State of New York, have invented new and useful Improvements in Window-Screens, of which the following is a specification.

This invention relates to improvements in window-screens for houses, coaches, &c., and has for its object to provide a screen attachment for sashes whereby when the sash is opened a screen will be automatically drawn out to cover or close the space left vacant by the sash.

15 A further object of the invention is to provide improved means whereby the screen is detachably secured to the sash.

With these and other objects in view the invention consists of certain novel features of construction, combination, and arrangement of parts, as will be hereinafter more fully described, particularly pointed out in the appended claims, and illustrated in the accompanying drawings, in which—

25 Figure 1 is a fragmentary front elevation of a window-sash casing and screen embodying my invention. Fig. 2 is a vertical central section, on an enlarged scale, through the sash and casing shown in Fig. 1. Fig. 3 is a 30 detail perspective view of the sash, illustrating the bail and manner of attaching the same to the sash. Fig. 4 is a fragmentary detail perspective view of the screen, illustrating the manner of attaching the connecting-plate 35 thereto.

Referring now more particularly to the drawings, the numeral 1 designates a window-sash, and the numerals 2 and 3 designate the sill and sides of a window-casing, in which 40 the sash is mounted.

Mounted in a chamber or recess 4 in the sill 2 is a spring-actuated shaft or roller 5, to which is secured one end of a flexible screen 6, which is adapted to wind thereon. This 45 screen is adapted to fit and move within a slot 7, formed in the upper rail of the sill 2, and is provided at its opposite or free end with a connecting device consisting of an angular or substantially L-shaped plate 8, to 50 the vertical flange of which the said free end of the screen is attached. This plate is formed

in the upper portion of its vertical flange with an opening 9 for the reception of a headed operating-pin 10, carried by a bail 11. The bail 11 is constructed of a single piece of resilient 55 material having its ends bent at right angles and perforated for the reception of screws or other suitable devices to secure the same to the under side of the bottom rail of the bail, which is recessed, permitting the bail to lie 60 flush when the window is in its closed position. The pin 10 has a slight outward and upward curvature, so as to project beyond the face of the sash and to permit the horizontal flange of the angular plate 8 to be clamped against 65 the under side of the bottom rail of the sash by the bail 11. The bail being composed of resilient material and secured at its ends will have a slight spring action, whereby the head of the pin, which forms a knob or finger-piece, may be grasped and the bail bent 70 downwardly to a sufficient extent to allow for the engagement and disengagement of the plate 8 with and from said bail, thereby permitting of the screen being attached to and 75 detached from the sash at will. When the screen is out of use and when the sash is closed, the vertical flange of the plate 8 occupies the slot 7, while the horizontal flange of said plate seats within a communicating 80 recess or countersink 12, formed in the upper face of the top rail of the sill 2, so that said flange will lie flush with the sill and allow the sash to close down to its fullest extent. When the sash is elevated, the screen 6 is 85 drawn outward to close a space or opening left thereby, and when the sash is closed the screen automatically winds upon the shaft or roller 5. The spring-actuated shaft or roller maintains the screen taut, no matter in what 90 position the sash is adjusted, whether the sash be fully or only partly opened, as will be readily understood.

It is apparent from the above description that the plate 8 may be attached to any form 95 of screen which is capable of sliding in and out of a recess in a sill, and therefore I do not wish it to be understood that I limit myself to a screen mounted upon a spring-actuated roller.

100 From the foregoing description, taken in connection with the accompanying drawings,

the construction, mode of operation, and advantages of the invention will be readily understood without a further extended description.

5 Having thus fully described my invention, what I claim as new, and desire to secure by Letters Patent, is—

1. The combination with a window sash and frame, of a screen mounted in a chamber in the sill, an L-shaped plate secured to the upper end of the screen, and provided with an opening, and a bail provided with an operating-pin to extend through said opening permitting the bail to engage the under side of the horizontal member of the plate securing it to the sash.

2. The combination with a sash and frame, of a screen mounted on the frame, a bail provided with an operating-pin and constructed 20 of a single piece of resilient material having

its ends bent at right angles, means for securing the bail to the sash, and means carried by the screen to be clamped, by the bail, securing the screen to the sash.

3. The combination with a window sash 25 and frame, of a screen mounted in a chamber in the sill, an L-shaped connecting-plate secured to the upper end of the screen and provided with a central opening, a bail provided with an operating-pin and constructed of a 30 single piece of resilient material having its ends bent at right angles and perforated, and means for securing said bail to the sash.

In testimony whereof I affix my signature in presence of two witnesses.

HENRY D. MILLS.

Witnesses:

PETER WAGNER,
J. L. ALLEN.
